UNITED STATES PATENT OFFICE.

GEORGE W. BARFIELD, OF NORTH BIRMINGHAM, ALABAMA.

CAR-COUPLING.

SPECIFICATION forming part of Letters Patent No. 787,819, dated April 18, 1905.

Application filed January 4, 1905. Serial No. 239,640.

To all whom it may concern:

Be it known that I, GEORGE W. BARFIELD, of North Birmingham, in the county of Jefferson and State of Alabama, have invented certain new and useful Improvements in Car-Couplers; and I do hereby declare the following to be a full, clear, and exact description of the invention, such as will enable others skilled in the art to which it appertains to make and use the same.

The primary object of this invention is to provide means for preventing water and foreign matter from entering the chamber of the draw-head through the opening formed to accommodate the locking-pin and which means also serves as a fulcrum for the pin when tilted by the inward swing of the knuckle; and further objects are to provide means for preventing the locking-pin from being forced laterally out of its proper plane and also to provide simple and inexpensive means for preventing water, &c., from entering the opening for the knuckle pivot-pin.

The invention will be hereinafter fully set forth, and particularly pointed out in the claims.

In the accompanying drawings, Figure 1 is a vertical longitudinal sectional view with the locking-pin shown in different positions. Fig. 2 is a plan view with the locking-pin in section. Fig. 3 is a view of the locking-pin removed.

Referring to the drawings, 1 designates the draw-bar, and 2 the chambered head having, as customary in this type of couplers, opposite jaws 3 and 4, and a knuckle 5, pivotally mounted between said jaws, such knuckle having a tongue 6, designed to swing inwardly within the chambered head. When the inner end of the tongue strikes the locking-pin 8, it will force the latter rearwardly until clear thereof, whereupon the locking-pin will swing forwardly and by engagement therewith of the squared portion 9 of the tongue will hold the knuckle locked. The knuckle is pivoted by a pin 10, the head whereof is formed on its under side with a groove to accommodate and fit upon a corresponding ridge 12 of jaw 3. By reason of

this construction the peripheral edge of the head of the pin being some distance beyond the groove and ridge, water and other foreign matter are prevented from entering the opening formed in the jaw and knuckle and also from coming in contact with the spring 13, which acts on the knuckle.

The locking-pin 8 is located centrally within the chambered head and fits between parallel walls 14, forming an upward central extension of such head. These walls support a cross-bolt 15, which is passed transversely through a longitudinal slot 16 in the locking-pin, such cross-bolt serving to prevent the latter from being raised too high in unlocking the knuckle. The opening in the top of head 2 is surrounded by a rectangular rib 17; but that portion of the rib forward of the opening is considerably higher than the remaining portions. The locking-pin is formed with a flange 18, which is designed when the pin is lowered to overlap the rib 17, and thereby prevent water, snow, and dirt from entering through the opening in the top of the head. That portion of flange 18 extending forwardly over the raised portion of rib 17 is higher than the remaining portion of such flange, so as to accommodate the increased height of the forward portion of such rib. This forms a fulcrum for the locking-pin upon which the latter swings when forced rearwardly by the engagement therewith of the inner end of the knuckle-tongue, as shown in dotted lines, Fig. 1. Thus the flange and coöperating rib which serve to prevent the entrance of water, snow, &c., through the locking-pin opening also act as the support for the locking-pin as the latter is moved rearwardly as the knuckle is being moved into place in the coupling. As soon as the knuckle has traveled its full extent, the locking-pin will by gravity swing forward, and its flange 18 will entirely surround the rib 17 and prevent entrance of foreign substances through the opening in the head.

I have shown at 19 a safety shoe or hook depending from the under side of the draw-head, so as to prevent an outwardly-drawn draw-head from falling beneath the car. This

safety-shoe fits in a socket on the under side of the draw-head, wherein it is secured by a bolt 21.

The advantages of my invention are apparent. It will be seen that I have provided extremely simple and inexpensive means for preventing the entrance of water, snow, and dirt into the openings for the pivot and locking pins and that the means provided for this purpose also serves as a fulcrum for the locking pin.

I claim as my invention—

1. The combination with the draw-head having a pivoted knuckle and an opening in its top, and a rib surrounding said opening, of the locking-pin fitted in said opening and having a flange for engaging said rib, said rib being higher at one point than another to form a fulcrum for said pin.
2. The combination with the draw-head having a pivoted knuckle and an opening in its top, and a rib surrounding said opening, the

forward portion of said rib being of greater height than the remaining portions thereof, of the locking-pin fitted in said opening and 25 having a flange surrounding said rib, that portion of the flange engaging the higher portion of the rib being higher than the remaining portions of said flange.

3. The combination with the draw-head having an opening and a rib or ridge surrounding said opening, of a knuckle, and a pivot-pin therefor fitted in said opening and having its head formed with a groove to accommodate said ridge, said groove being some distance inwardly from the periphery of said head. 30

In testimony whereof I have signed this specification in the presence of two subscribing witnesses.

GEORGE W. BARFIELD.
